J. F. OHMER

HOLDING MEANS FOR DATE SETTING DEVICES

Filed Oct. 22, 1926

UNITED STATES PATENT OFFICE.

JOHN FRANCIS OHMER, OF DAYTON, OHIO, ASSIGNOR TO OHMER FARE REGISTER COMPANY, OF DAYTON, OHIO, A CORPORATION OF OHIO.

HOLDING MEANS FOR DATE-SETTING DEVICES.

Application filed October 22, 1926. Serial No. 143,321.

This invention relates to an improved means for holding or locking gears connected with printing wheels in position after they have been set, and constitutes an improvement on the structure shown in the application of Albert S. Wheelbarger and Grover C. Coil, Serial No. 65,532, filed October 29, 1925.

Many machines are provided with printing wheels or indicating wheels to show the month, day and year in which the transaction recorded occurred. As instances of such machines might be mentioned cash registers and the machine in the aforementioned application.

In the drawings:

Fig. 1 is a front elevational view,

Fig. 2 is a cross-sectional view on the line 2—2 of Fig. 1, looking in the direction of the arrows;

Fig. 3 is a detailed plan view of the mechanism shown at the right hand part of Fig. 1,

Fig. 4 is a fragmentary side elevational view of the right hand end of the casing,

Fig. 5 is a cross-sectional view on the line 5—5 of Fig. 1, looking in the direction of the arrows, and

Fig. 6 is a cross-sectional view taken on the line 6—6 of Fig. 4, looking in the direction of the arrows.

Referring more particularly to the drawings in which like reference characters are used throughout to designate similar parts;

Knurled disks 1, 2 and 3 are provided on which are indications to denote the month and day. The month disk 1 is connected to a sleeve 4 which carries a gear 5 which meshes with a gear 6 secured to a printing wheel or visual indicator 7, on which are affixed characters to represent the months. The gears 5 and 6 are provided with twelve teeth for the twelve months. The disk 2 is connected to a sleeve 8 within the sleeve 4, which sleeve 8 carries a gear 9 which meshes with a gear 10 on a shaft 11, which gear 10 has integrally secured thereto a printing or visual disk 12. In like manner, the disk 3 is secured to a shaft 13 within the sleeve 8, which shaft 13 carries a gear 14 which meshes with a gear 15 on the shaft 11, which gear 15 has integrally secured thereto a

printing or visual disk 16. The gears 9, 10, 14 and 15 are provided with ten teeth corresponding with the number of numerals on the date setting wheels 2 and 3, and the printing or visual disks 12 and 16 are each provided with ten characters from zero to nine inclusive corresponding to the numerals on the disks 2 and 3. The gear 17 on the shaft 13 integrally meshes with the gear 18 on the shaft 11, which gear is rigidly secured to a printing or visual disk 19 which has the years on its periphery. The gear 17 is manually operated by means of any suitable instrument such as a screw driver. It is, therefore, obvious that by engaging the disks 1, 2 and 3 with the thumb, the printing or visual disks 7, 12 and 16 are rotated so as to indicate the proper month and day. Once a year it is necessary to change the year wheel 19 and this, as above mentioned, is accomplished by rotating the gear 17 by any suitable instrument. The shaft 4 is mounted in an intermediate plate 20 and in one of the sidewalls 21 of the machine, while the shaft 11 extends between the sidewalls 21 and 22 of the machine. The shaft 11 also carries wheels 23 provided with suitable characters to indicate other data, which wheels 23 are actuated from the hand operated members 24, all of which structure is fully described in the said application of Wheelbarger and Coil, Serial No. 65,532.

If the disks on the shaft 11 are to be used as printing disks, as is indicated in Fig. 2, a platen holder 25 may be employed mounted on a shaft 26 which platen holder carries two platens 27 and 28 and an inking roller 29. As the platen holder 25 is oscillated as described in the aforementioned application, the platens 27 and 28 and the inking roller 29 are moved across the faces of the disks on the shaft 11. Naturally this tends to rotate the disks 23 on the shaft 11. The wheels 23 are held against such rotation by means shown in said copending application, but the date wheels 7, 12, 16 and 19 have heretofore not been provided with any suitable means to hold them against accidental rotation, as, for instance, the accidental rotation imparted by the rollers 27, 28 and 29 moving across the face of same.

A U shaped member 30 is journaled on a

shaft 31, which U shaped member is provided with arms or side members 32, one of which members is provided with an extension 33 which may be grasped by the hand of the operator. The arms 32 are provided with a hole 34 through which passes the shaft 31. If desired, a spacing sleeve 35 may be interposed between the arms 32. One of the arms 32 carries a pin 36 which projects on both sides of the arms 32 and is adapted to engage the gears 9, 14 and 17, each of which gears is a ten-toothed gear. The same arm 32 is provided with an off-set finger 37 as is clearly shown in Fig. 5, which finger is curved and terminates in a reduced portion adapted to fit between the teeth on the twelve-toothed gear 5.

The other arm 32 is provided with a circular cutaway portion 38 adapted to receive the end of a pin 39 carried by a spring 40 secured to the wall 21 of the machine. The pin or plunger 39 is provided with a beveled end so as to be readily fitted into the cutaway portion 38 and to resiliently hold the member 30 against movement. When, however, the operator grasps the extension 33, the plunger readily yields against the tension of the spring 40 so that the member 30 can be moved to disengage the pin 36 and finger 37 from the gears 5, 9, 14 and 17 so that the disks 1, 2 and 3 can be operated to change the date. The right hand arm 32 is also provided with a rectangular cutaway portion 41 which receives a pin 42 carried by the wall 21 of the machine. The ends of the cutaway portion 41 and pin 42 limit the movement in either direction of the member 30.

In operation, the pin 36 and finger 37 normally engage their respective gears so that accidental rotation cannot be imparted to the printing disks. When it is desired to change the date, however, the operator grasps the projection 33 and raises it while the plunger 39 is disengaged from the cutaway portion 38 against the tension of the spring 40. The disks 7, 12, 16 and 19 can now be actuated by means of the disks 1, 2 and 3 and the gear 17. As soon as the date has been reset the operator lowers the projection 33 so that the pin 36 and finger 37 engage their respective gears, locking the same against accidental rotation while the plunger 39 is moved into engagement with the cutaway portion 38 by means of the spring 40, thereby resiliently holding the member 30 and extension 33 against being raised.

Obviously, many changes might be made in the specific form shown by way of example in this application. It is, therefore desired to claim the invention broadly in whatever form it may be embodied, except as I may limit myself in the appended claims.

Having now described my invention, I claim:

1. In a machine of the type described, a plurality of gears, one of said gears having a different number of teeth from the other of said gears, an arm provided with an extension adapted to be actuated by the hand of the operator, a pin and a finger carried by said arm, said pin being adapted to engage the gears of uniform number of teeth and said finger to engage the gear having a different number of teeth.

2. In a machine of the type described, a plurality of gears, one of said gears having a different number of teeth from the other of said gears, a pivoted arm having an extension adapted to be manually operated, a pin and a finger carried by said arm, said pin engaging between adjacent teeth on the gears having a uniform number of teeth, and said finger engaging between two teeth of the gear having a different number of teeth.

3. In a machine of the type described, a plurality of gears, one of said gears having a different number of teeth from the other of said gears, an arm provided with an extension adapted to be actuated by the hand of the operator, a pin and a finger carried by said arm, said pin being adapted to engage the gears of uniform number of teeth and said finger to engage the gear having a different number of teeth, and means to limit the movement of said arm.

4. In a machine of the type described, a plurality of gears, one of said gears having a different number of teeth from the other of said gears, an arm provided with an extension adapted to be actuated by the hand of the operator, a pin and a finger carried by said arm, said pin being adapted to engage the gears of uniform number of teeth and said finger to engage the gear having a different number of teeth, and means to hold said arm in position after the same has been lowered to engage said pin and finger to lock said gears.

5. In a machine of the type described, a plurality of gears, one of said gears having a different number of teeth from the other of said gears, an arm provided with an extension adapted to be actuated by the hand of the operator, a pin and a finger carried by said arm, said pin being adapted to engage the gears of uniform number of teeth and said finger to engage the gear having a different number of teeth, means to limit the movement of said arm in either direction, and means to hold said arm after the same has been lowered so as to engage said pin and finger in locked position with said gears.

6. In a machine of the type described, a shaft, date printing disks rotatably mounted

on said shaft, gears operatively connected with each of said disks, a second shaft, each of said last mentioned gears intermeshing with one of the first mentioned gears, means whereby said second mentioned gears are rotated to actuate the first mentioned gears and said disks, means whereby said second

mentioned gears are locked against rotation, said means consisting of a manually operated arm, and means carried by said arm to engage said second mentioned gears to hold the same against accidental rotation.

In testimony whereof I affix my signature.

JOHN FRANCIS OHMER.
